RACK FOR ASH TRAYS

Duane O. Jackson, Waterloo, Iowa, assignor to Distinguished Gift Manufacturers, Inc., Waterloo, Iowa, a corporation of Iowa

Filed Oct. 27, 1960, Ser. No. 62,643

Term of patent 7 years

(Cl. D33—3)

FIG. 1

FIG. 2

FIG. 3

FIG. 4

FIG. 5

Fig. 1 is a perspective view of this rack for ash trays, showing my new design;

Fig. 2 is a top plan view;

Fig. 3 is an end elevational view;

Fig. 4 is a side elevational view; and

Fig. 5 is a bottom plan view thereof.

The dotted line indication of ash trays in Fig. 1 is for illustrative purposes only.

I claim:

The ornamental design for a rack for ash trays, as shown and described.
